APPLICATOR FOR DYE AND THE LIKE

Fredrick E. Beebe, Willoughby, Ohio

Application April 9, 1949, Serial No. 86,921

4 Claims. (Cl. 132—13)

1

The invention relates to applicator means for simultaneously combing the hair and applying treating fluid thereto. It is particularly adapted to the application of hair dye to the hair while protecting the scalp from discharge of dye thereon.

This application is a continuation in part of my copending application Serial No. 667,200, filed May 3, 1946, now abandoned.

An object of the invention is to provide novel and improved means associated with a hair comb for retaining a quantity of fluid when the comb is not in use, and for continuously discharging a fresh quantity of fluid adjacent the comb teeth as the previously discharged fluid is removed by the combing operation.

Another object of the invention is to provide a novel comb of the type described wherein a liquid holding reservoir runs longitudinally of the comb and communicates with a wick-receiving channel so constructed that a wick-inserting and wick-removing tool may be passed into the reservoir.

Still another object of the present invention is the provision of a novel reinforced wick for use in a comb of the type described.

Other objects and advantages will be apparent from a study of the following specification in conjunction with the accompanying drawings showing one embodiment of the invention in which:

Fig. 1 is a longitudinal sectional view through a hair comb embodying my invention, the parts being shown in side elevation;

Figs. 2 and 3 are elevational views from respectively the left and right ends of Fig. 1;

Figs. 4 and 5 are sectional views taken respectively on lines 4—4 and 5—5 of Fig. 1;

Fig. 6 is a sectional view generally similar to Fig. 4, but showing a slightly modified form of the invention;

Fig. 7 is a longitudinally extending sectional view through a modified form of my device showing an improved wick and wick-inserting tool which has moved the wick partially into its receiving channel;

Fig. 8 is a sectional view taken along the line 8—8 of Fig. 7 but showing the wick and inserting tool in their fully inserted position;

Fig. 9 is a sectional view taken at the right hand end of Fig. 7 and showing a tool in position to remove the wick;

Fig. 10 is a transverse sectional view taken along the line 10—10 of Fig. 8;

Fig. 11 is a transverse sectional view taken along the line 11—11 of Fig. 9; while

Fig. 12 is a top plan view of one end of the novel

2

wick showing the manner of gripping the same with the inserting tool.

Referring now to the drawings, there is shown a hair comb body 10 having the usual series of spaced teeth 11. The comb body is provided with a longitudinal trough or channel 12 opening towards the teeth, and, in the embodiment shown, communicating with the inner ends of the spaces 13 between the teeth. The comb is further provided with a handle portion 14 connected with the comb by means of a neck 15. In the embodiment shown the neck terminates in a threaded socket 16 and the handle 14 has a complementary threaded plug 17 seatable in the socket.

The handle carries a fluid receptacle or bulb 18 which, as here shown, is made of rubber or similar resiliently yieldable and leak-proof material. The bulb is provided with a discharge neck 19 surrounding and gripping a hollow nipple 20 attached to the handle. Said nipple is in communication with channel 12 through a passageway 22 extending centrally through plug 17. At its right end the bulb 18 has an intake spout 24 provided with an intake port 25 extending therethrough. The spout is provided with a removable closure member, such as screw cap 26.

It will be apparent that the bulb 18 may be filled in the conventional manner by compressing its resilient walls and inserting intake spout 24 into the treating fluid, thereafter permitting the fluid to be sucked into the expanding bulb. A check valve 27 within nipple 20 prevents reverse flow of fluid or air through channel 12 and passageway 22 into bulb 18.

Seated in channel 12 is a wick 30 which lies partly in the channel and extends partly outwardly into the inner ends of the spaces 13 between the teeth, as best seen in Figs. 1 and 5. When it is desired to use the applicator, the bulb 18 is compressed so as to discharge a quantity of fluid through passageway 22 to wick 30. During the operation of combing the hair, the fluid is transferred to the hair from the exposed portions of the wick, being continuously replaced by fresh fluid from the body of the wick and its feeding channel.

In order to insure an even distribution of the fluid to the wick 30, a longitudinal bored aperture 31 is provided immediately adjacent and parallel to channel 12, the aperture communicating with the channel through a necked slot 32. The fluid first completely fills the unobstructed aperture or reservoir portion 31 when the bulb 18 is slightly compressed, and thereafter the fluid flows to the wick through slot 32. As will be seen by reference to Fig. 1, the space 33 between the

inner end of plug 17 and the inner face of socket 16 constitutes a header space communicating both with channel 12 and with aperture 31.

Fig. 6 shows a slightly modified embodiment of the invention wherein the wick 30 has incorporated therein a stiffening strip 34 of metal or other suitable material. The strip extends longitudinally throughout substantially all of the length of the wick. The practical advantage of strip 34 is that it aids in the insertion of the wick in channel 12. Such aid will be appreciated when the wick material is a snug fit in the channel.

The advantage of a structure of the nature just described will be particularly apparent in connection with its use for applying dye fluid to the hair. As is well-known to those who have attempted to use hair dye, one of the disadvantages of the operation lies in the fact that it is difficult to evenly distribute the dye, and consequently the dye has a tendency to flow inwardly over the scalp. This results in imparting to the scalp a disagreeable color which detracts from the natural appearance of the scalp and hair. When dye is applied by means of the device just described, substantially all of the dye is applied evenly to the hair and very little or none comes in contact with the scalp.

If the bulb 18 is of non-resilient material, it will act as a dye reservoir and feed to wick 30 if ball check 27 is omitted. But I prefer the positive feed provided when bulb 18 is of rubber or the like.

A modified form of my device is shown in Figs. 7 to 11 inclusive. In this form, the comb 35 has a plurality of parallel teeth 36 in the usual manner. Extending longitudinally through the comb is a reservoir 37 which is somewhat of a keyhole shape as more clearly shown in Figs. 10 and 11. It includes a generally cylindrical reservoir proper 37a and a depending trough 37b which is cut through the bases of the teeth 36 as clearly shown in Fig. 7. The reservoir 37 communicates at the right hand end of Fig. 7 with a recess 38 which may be threaded to receive a rubber bulb 14 like that described in connection with Fig. 1, or the rubber bulb may have a force fit in the recess 38. The reservoir portion 37a is large enough to receive a wick-inserting tool 39 embracing a reinforced wick construction as shown in Figs. 7 and 8, as will be later more fully described.

The present invention also includes a novel form of wick for use in the comb just described. In this form of wick, a strip of stiff reinforcing material 40 is embraced by wicking material 41 which is folded in U-form so as to extend down one side of the strip 40, fold under the bottom, and extend up the other side. Preferably, the strip 40 is of a material which is readily perforated by the needle of a sewing machine of standard character so that the wicking may be secured to the strip 40 by a line of stitching 42. It will be noted that the width of the strip 40 when measured in the general direction of the plane of teeth 36 is substantially equal to the depth of the reservoir 37a plus the trough 37b when measured in the same direction minus the thickness of the wicking. This is clearly seen in Figs. 10 and 11. The line of stitching 42 is positioned to lie near that side of the reservoir 37a which is nearer to the channel 37b. In fact, in the form shown, it is approximately along the zone where the reservoir 37a meets the trough 37b. This leaves free edges 41a along the top of the wicking parallel to the upper edge of the

strip 40 for insertion of the tool 39 as will presently appear.

For inserting and removing the wick in the comb structure, I provide the special tool 39 mentioned above. This comprises a handle portion 39a having a bifurcated end including the two arms 39b and 39c extending from the handle. A cheap form of this device is provided by bending a strip of metal back upon itself in one continuous form to provide the parts 39a, 39b and 39c. A sleeve 39d may then be slipped upon the bifurcated end to maintain the grip of these ends on the wick between them. The manner of gripping the wick for inserting the same in the comb will be clearly seen in Figs. 7, 8, 10 and 12. The tool 39 is applied to the wick as shown in Fig. 12. The bifurcated ends 39b and 39c are spread apart to receive the reinforcing strip 40 between them. The tool 39 is applied to the strip 40 along its upper edge as clearly shown in Fig. 10 and above the line of stitching 42. The lips 41a of the upper end of the wicking part easily permit this operation. The tool and wick are then inserted longitudinally into the aperture in the comb as shown in Figs. 7 and 8. The sleeve 39d pressing against the end of the strip 40 as shown in Fig. 8 shoves the wick home to its final position as shown there.

The removal of the wick is illustrated in Fig. 9 using the longer arm 39b of the tool 39. This longer arm has its tip end turned over as indicated at 39e to provide a short hook. The strip 40 has an aperture 40a drilled through it at the end nearer the mouth 38 of the comb. This opening may have registering openings through the wicking 41 although this is not necessary as the lips 41a may be parted to permit the insertion of the hook 39e through the opening 40a as shown in Fig. 9. A pull on the wick then removes it from the comb. It will be noted that the opening 40a is located above the line of stitching 42 for easy access in removal. The operation of the modification shown in Figs. 7 to 12 inclusive is similar to that of my first described form. Liquid to be applied to the hair may be placed in the rubber bulb 14 or a similar bulb which is attached to the mouth 38 of the comb 35. A small amount of the liquid may then be squeezed into the reservoir portion 37a where it will get into the wicking 41 and be carried to the bases of the teeth 36 for direct contact with the hair as the comb is drawn through the same. At the same time, I have provided a wick with its central reinforcing strip 40 and a line of stitching 42 attaching the wicking to the reinforcement so that the wicking does not ball up or get out of place in use. At the same time, the reservoir 37 is made large enough to receive the tool 39 gripping the strip 40 for insertion of the wick, as otherwise users would have difficulty in making efficient use of my invention. The removal of the wick is very easy as illustrated in Fig. 9.

What I claim is:

1. A comb for the purpose described comprising a unitary comb body provided with a series of spaced teeth extending from one side thereof, said body and teeth lying generally in the same plane, said body having a passageway extending longitudinally through the central portion thereof, said passageway being of substantially uniform section throughout its length, said passageway being generally of key-hole form in section and having a generally cylindrical portion communicating with a trough portion, said trough portion passing through the bases of the comb

5

teeth and communicating directly with said teeth, and a wick lying in both portions of said passage-way, said wick having a sheet of wicking folded in U-form about a strip of stiff reinforcement, said trough portion being of a width to snugly receive said wick and said cylindrical portion being wider than said trough portion to receive said wick plus an inserting instrument.

2. The combination of claim 1 wherein a row of stitching secures said sheet of wicking to said reinforcement, said row of stitching extending generally parallel to, and on the trough portion side of, the axis of said cylindrical portion.

3. A wick for use in a comb of the type described and comprising an elongated rectangular flat strip of stiff reinforcement, and a sheet of wicking folded over one of the longitudinal edges of said reinforcement and secured thereto.

4. A wick for use in a comb of the type de-

6

scribed and comprising an elongated rectangular flat strip of stiff reinforcement, and a sheet of wicking folded over one of the longitudinal edges of said reinforcement, portions of said wicking extending along both flat sides of said strip, and a row of stitching parallel to said one longitudinal edge and securing said wicking portions to said reinforcement.
